UNITED STATES PATENT OFFICE.

EDWARD GEORGE KUBLER, OF WURZBURG, GERMANY.

CURRYCOMB.

SPECIFICATION forming part of Letters Patent No. 673,876, dated May 14, 1901.

Application filed April 4, 1901. Serial No. 54,362. (No model.)

To all whom it may concern.

Be it known that I, EDWARD GEORGE KUBLER, a citizen of the United States, residing at Wurzburg, Bavaria, Germany, have invented a certain new and useful Improvement in Currycombs, of which the following is a specification.

My invention has relation to improvements in currycombs; and one object of my invention is to produce an article of the kind named in which the comb and back shall be of a single sheet of metal, in which the comb edges shall not be serrated, thereby avoiding tearing or abrading the skin or pulling out the hair, but pushing the dirt along and out of the hair, and which shall be parts of the same sheet of metal. The spaces between the comb edges will be rounded, thus preventing any sharp corners to hold the matter removed.

20 A further object is to reinforce the comb at suitable intervals by metallic straps, one of which shall embody a ring to act as a handle and a part to operate as a hand-rest, and a final object is to secure great lightness and

25 strength in the same comb.

To the aforesaid objects my invention consists in the peculiar and novel construction, arrangement, and combination of parts hereinafter described and then specifically pointed out in the claims, reference being had to the accompanying drawings, forming a part of the specification.

In the accompanying drawings, in which similar reference-numerals indicate like parts in the different views, Figure 1 is an end or edge elevation of a sheet of metal molded to form my improved currycomb. Fig. 2 is a section of the complete comb at the line *xx* of Fig. 3, and Fig. 3 a plan of the complete

40 comb.

Referring to the figures, 1 is a sheet of metal, preferably steel, of the proper width and length to form the comb and back, bent intermediately into a tube 2, open between

45 the halves, the upper half terminating in an upturned edge 3, and the lower half bent transversely into a series of semicircular grooves, with the intermediate portions bent sharply to form the comb edges, and its end also having

50 an upturned edge 4 to pass outside of and be bent over the edge 3. Through the tube 2 is

passed a bolt or rod 5, having rounded heads at each end. This rod may be placed in the tube 2 before the latter is closed or the plate 1 may be bent around it primarily. The upper 55 and lower halves are then pressed together, and on them is centrally placed a bar 6, bent at the front end into a ring 7 to form a handle and having a curve 8 to form a hand-rest and secured by rivets 9, that pass through it 60 and both halves of the plate 1, thus uniting these parts. The ring 7 may be and preferably is lined with vulcanized rubber to present a soft surface to the thumb in using the brush. To reinforce and strengthen the 65 brush, metal bars 10 are placed on the back flush with the edge and secured by rivets 11.

In use the thumb is passed through the ring 7, with the hand resting on the back of the brush, with the curve 8 in the hollow of 70 the hand, thus giving the hand a firm grip to manipulate the brush.

Having thus described my invention, what I claim, and desire to secure by Letters Patent, is—

1. An improved currycomb consisting of a sheet of metal folded centrally about a bolt, with one-half bent transversely into semicircular grooves with the intermediate portions bent sharply, and a metallic bar having an end 80 ring and an intermediate loop secured to the back of said metal sheet by rivets passing through both folds thereof, substantially as shown and described.

2. An improved currycomb consisting of a sheet of metal folded centrally about a bolt, with one-half bent transversely into semicircular grooves with the intermediate portions bent sharply, and a metallic bar having an end ring and an intermediate loop resting centrally on said back, and end bars resting on said back flush with the edges, said bars secured by rivets passing through both folds of the metal sheet, substantially as shown and described.

3. An improved currycomb consisting of a sheet of metal folded centrally about a bolt, with one-half bent transversely into semicircular grooves with the intermediate portions bent sharply, and a metallic bar having an end 100 ring and an intermediate loop secured to the back of said metal sheet by rivets passing

through both folds thereof, and a vulcanized-rubber lining for said ring, substantially as shown and described.

4. An improved currycomb consisting of a sheet of metal folded centrally about a bolt, with one-half bent transversely into semicircular grooves, with the intermediate portions bent sharply, the ends brought together and one folded over the other, and a metallic bar having an end ring and an intermediate loop,

secured to the back of said metal sheet by rivets passing through both folds, substantially as shown and described.

In testimony that I claim the above I hereunto set my hand in the presence of two ¹⁵ subscribing witnesses.

EDWARD GEORGE KUBLER.
